(57) **CLAIM**

An ornamental design for a packaging box, as shown and described in the drawings.

DESCRIPTION

FIG. 1 is a front perspective view of the packaging box.

FIG. 2 is a front view of the packaging.

FIG. 3 is a rear view of the packaging box.

FIG. 4 is a right side view of the packaging box.

FIG. 5 is a left side view of the packaging box.

FIG. 6 is a top view of the packaging box; and,

FIG. 7 is a bottom view of the packaging box.

1 Claim, 5 Drawing Sheets
